UNITED STATES PATENT OFFICE

GEORGE K. SNOW, OF WATERTOWN, MASSACHUSETTS.

IMPROVEMENT IN HOLDERS FOR BILLS, NOTES, &c.

Specification forming part of Letters Patent No. 36,734, dated October 21, 1862.

To all whom it may concern:

Be it known that I, GEORGE K. SNOW, of Watertown, in the county of Middlesex and State of Massachusetts, have invented a new and Improved Holder for Bills, Notes, &c., for use in stores, ticket and other offices; and I do hereby declare that the following, taken in connection with the drawings, which accompany and form part of this specification, is a description of my invention sufficient to enable those skilled in the art to practice it.

The object of my invention is to meet a want inaugurated by the present extensive use of paper currency, especially by the introduction of the "Postage Currency."

It consists in a holder of peculiar construction, having reference to facility of packing and withdrawing notes, bills, or tickets, and to their security in the positions assigned them.

The holder consists in a trough or tray having four boundary faces--viz., a back, two sides or ends, and a bottom inclined from a horizontal plane, when said trough is combined or is provided with a presser, which is attached to the tray so that the presser will by swinging, lifting, or rolling, admit beneath it, and so that the weight of the presser will rest thereupon, one or more notes, bills, tickets, &c., of a size suited to the trough.

In Figure 1 of the drawings there is shown in section a series of three of such angular troughs or trays, each of which has its presser attached, though the method of attaching the presser is shown varied in each of the three instances. The construction, however, which

I prefer is that of the tube placed loosely upon a fixed rod, as this presser is readily lifted by the contact of the fingers therewith when these present a limp and crumpled note for deposit beneath the presser. The plan, Fig. 2, shows a combination of several of the trays or troughs with their respective pressers, and also with two cup-shaped specie-receptacles and a sponge-cup, showing how a useful combination of my invention may be made, which, with proper and evident modifications, will recommend it for use in all "cash-drawers," ticket and other offices, banks, &c.

Fig. 1 is a section taken in the line *a a*, Fig. 2.

By inspection of the drawings it will be seen that the angular construction of each tray or trough is such as will permit the withdrawal of the last note or ticket from beneath the presser on the plane of the bottom, which could not be done if the tray were made with a front side, or otherwise than with substantially the angular form of cross-section shown.

I claim—

1. As a new article of manufacture, the tray or trough when made with a cross-section, substantially as shown, and provided with a presser connected therewith and operating substantially as described.
2. The combination of two or more such trays or troughs and their respective pressers, substantially as shown.

GEORGE K. SNOW.
